UNITED STATES PATENT OFFICE.

J. TALMAN BUDD, OF BUFFALO, NEW YORK.

ATTACHMENT FOR SUSPENDERS.

SPECIFICATION forming part of Letters Patent No. 355,133, dated December 28, 1886.

Application filed March 31, 1886. Serial No. 197,280. (No model.)

To all whom it may concern:

Be it known that I, J. TALMAN BUDD, a citizen of the United States, residing at Buffalo, in the county of Erie and State of New York, have invented certain new and useful Improvements in Attachments for Suspenders; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 My invention relates to improvements in attachments which are adapted for use, combined or singly, with suspenders, drawers supports, or other analogous devices, all as will be more fully hereinafter described and claimed.

20 In the drawings, Figure 1 is a front view of my improved combined buckle or clamp and clasp. Fig. 2 is a rear view of the same. Fig. 3 is a side view of the same. Fig. 4 is a front view of the hanger. Fig. 5 is another view 25 of the same illustrating method of construction. Fig. 6 is a back view of modified form of buckle or clamp, shown applied to drawers supports. Fig. 7 is a side sectional view of same, and Figs. 8, 9, and 10 are detached 30 tail views.

Referring to the drawings, *a* is the frame in which the clamping device operates, and through which the suspender-webbing passes. Its front wall, *a'*, is curved transversely, as 35 shown in Figs. 1 and 3. At its sides, and extending inwardly, parallel with the front wall, are the curved flanges *a²* *a²*, (see Fig. 2,) provided with the vertical slots *a³* *a³*. The transverse indentation *a⁴* forms an inner shoulder, 40 *a⁵*, in the frame, as shown in Fig. 3.

b is the main body of the clamping device, which is of a sharper curve than the side flanges, *a²* *a²*. Across this portion *b* are the indentations *b'*, producing spurs upon its inner face, for frictional contact with the webbing. On either side of the portion *b*, near its upper edge, are the lugs *b²* *b²*, which pass through the slots *a³* *a³* and over upon the curved flanges *a²* *a²*, for the purpose of adjustably securing 50 the clamping device in the frame. At the lower end of the portion *b* is the outwardly-

curved portion *b³*, with the inwardly-turned serrated lip *b⁴*. From the lower edge of the portion *a'* of the buckle *a* extends the frame *c*, centrally arranged, within which is the spring- 55 strip *c'*, its lower free end being provided with the shouldered portions *c²* *c²* and the inwardly and downwardly projecting tongue *c³*, forming a shoulder. The lower end of the frame *c* is turned inwardly, forming the shoulder *c⁴*, and 60 downwardly, forming the flange *c⁵*. The lip *c⁶*, in the same plane with the flange *c⁵*, extends inwardly to a point near the lower end of the spring-strip *c'* *c³*. The cutting of the frame *c* forms the slot *c⁸* for the reception and retention of the hanger. 65

d is the frame of the hanger, upon the upper portion of which is the T-shaped projection *d'*, having its ends *d²* *d²* turned upwardly, as shown. The downwardly-extending portions 70 *d³* *d³* of the frame, with the inwardly extending lugs *d⁴*, are stamped or cut in the form shown in Fig. 5, and by bending in these portions *d³* *d³* the lugs *d⁴* are caused to engage with the hollow rollers *e* *e*, forming the complete hanger 75 shown in Fig. 4.

The clasp and hanger just described are improvements in the construction covered by Letters Patent No. 329,434, granted to me on 80 the 3d day of November, 1885.

In Figs. 6, 7, and 10 is shown the modification applied to the end of a drawers-support, in which *f* is the frame, in the form of a hollow rectangular box with open ends. Within this box *f* is adjustably placed the clamping device, 85 of which *f'* is the main body, having at its upper end the lip *f²*. *f³* is a curved portion adapted to exert a spring-pressure against the strap to be secured, and at the lower end is the inwardly-turned serrated lip *f⁴*. 90

The operation of the clamp or buckle shown in Figs. 1, 2, and 3 is as follows: The webbing *g* of the shoulder-strap is passed between the curved wall *a'* of the frame and the clamping device *b*, as shown in Fig. 3. By pushing up the clamping device the serrated lip *b⁴* catches the webbing and holds the same firmly against the shoulder *a⁵*, the spurs formed by the indentations *b'* preventing the accidental disengagement of the serrated lip *b⁴* 100 from the webbing when the strain is removed. In loosening the clamp from the webbing by

holding the frame and pulling the webbing downwardly, the clamping device *b* drops down, and the lower serrated lip, *b*⁴, by reason of the curved form of both clamping device 5 and frame, is swung out, as shown in dotted lines in Fig. 3, in order to clear it from contact with the webbing. The projecting lugs *b*², which slide in the slots *a*³ of the curved flanges *a*² as the clamping device is moved either way, being within the curved portion, do not therefore project and cause injurious contact with the clothing.

In the operation of the form shown in Figs. 6, 7, and 10 the clamping device, as it is 5 pushed up within the box *f*, brings the serrated lip *f*⁴ in contact with the drawers-support strap passing through the box *f*, firmly holding it against the shoulder *f*⁵, formed by the lower front edge of the box *f*. The curved portion *f*³, being then within the box and pressing upon the strap *h*, prevents the accidental disengagement of the serrated lip *f*⁴ from the strap *h*.

The curved clamping device *b* (shown in Figs. 5 1, 2, and 3) could be operated within a straight frame; but the curved form shown enables the serrated lip to be thrown farther from the strap *g* when it is disengaged.

The T-shaped hanger shown in Fig. 4 is engaged with the spring-clasp as follows: The turned-up ends *d*² of the T are inserted in the slot *c*⁸, catching under the inner edges of the frame *c*, passing over the spring-strip *c*', and guided by the turned-up edges *d*² *d*² into the lower portion of the slot *c*⁸, resting within and under such slot and upon the portion *c*⁴ on either side of the slot, the hanger being in front of the portions *c*⁵ and *c*⁶ of the frame. The shoulder formed by the tongue *c*³ and the shouldered portions *c*² *c*² of the spring-strip *c*', together with the turned-up ends *d*² *d*² of the T, prevent the accidental disengagement of the hanger from the clasp.

The clasp above described may be called a "smooth-surfaced clasp"—that is, having its frame and spring on the same plane; and as a hanger with turned-up points or ends other than one that is strictly T-shaped could be used in connection therewith, I do not wish to confine the use of the clasp to a T-shaped hanger.

I claim—

1. An attachment for suspenders, &c., having a clamping device consisting of a curved plate adjustably arranged within a frame, and having a lower serrated edge adapted to operate in conjunction with a shoulder in the frame, and a raised portion or portions to hold the serrated edge in engagement with the strap

which passes through the frame, and a clasp 60 consisting of a frame having a slot within or under which is provided a shoulder, such slot being adapted for the reception of a T-shaped hanger, substantially as shown and described.

2. A clasp consisting of the frame *c*, the slot *c*⁸, the shoulder *c*⁴, flange *c*⁵, and lip *c*⁶, and the spring-strip *c*', with shouldered portion *c*² and tongue *c*³, in combination with a hanger, substantially as shown and described.

3. The combination, with the clasp consisting 70 of the frame *c*, having the slot *c*⁸, the shoulder *c*⁴, flange *c*⁵, and lip *c*⁶, and the spring-strip *c*', with shouldered portions *c*² and tongue *c*³, of the hanger having the T head *d*', with the turned-up ends *d*² *d*², substantially as and for 75 the purpose stated.

4. A buckle consisting of a curved plate or clamping device adjustably arranged within a frame, and having a lower serrated edge adapted to operate in conjunction with a 80 shoulder in the frame, and a raised portion or portions to hold the serrated edge in engagement with the strap which passes through the frame, in combination with a clasp or hanger, for the purpose stated. 85

5. In a buckle, the combination, with the curved frame *a*, having the curved flanges *a*² *a*² and the shoulder *a*⁵, of the curved clamping device *b*, provided with the serrated edge *b*⁴, and of a clasp or hanger, for the purpose set 90 forth.

6. In a buckle, the combination, with the curved frame *a*, having the curved and slotted flanges *a*² *a*² and the shoulder *a*⁵, of the curved clamping device *b*, provided with the lugs *b*² *b*², the indentations *b*¹, and the serrated edge *b*⁴, and of the hanger *d*, substantially as shown 95 and described.

7. The combination, with a clasp having its frame and spring in the same plane, of a hanger having turned-up points or ends to guide it into engagement with the clasp and prevent accidental disengagement therefrom, substantially as shown and described. 100

8. The combination, with a clasp having its frame and spring in the same plane, of a T-shaped hanger having its T-head provided with turned-up ends or points to guide it into engagement with the clasp and prevent accidental disengagement therefrom, substantially 105 as shown and described. 110

In testimony whereof I have signed my name to this specification in the presence of two subscribing witnesses.

J. TALMAN BUDD.
